(57) **CLAIM**

I claim the ornamental design for a towel, as shown and described.

DESCRIPTION

FIG. 1 is a perspective of my new design for a towel, wherein the towel is in an unfolded configuration;

FIG. 2 is top view thereof;

FIG. 3 is a front view thereof, the rear view being a mirror image of the front view;

FIG. 4 is a left side view thereof, the right side view being a mirror image of the left side view;

FIG. 5 is a perspective view thereof, wherein the towel is in a folded configuration;

FIG. 6 is a perspective of another embodiment of my new design for a towel, wherein the towel is in an unfolded configuration;

FIG. 7 is top view thereof;

FIG. 8 is a front view thereof, the rear view being a mirror image of the front view;

FIG. 9 is a left side view thereof, the right side view being a mirror image of the left side view;

FIG. 10 is a bottom view thereof; and,

FIG. 11 is a perspective view thereof, wherein the towel is in a folded configuration.

The broken lines form no part of the claimed design.
